Peter A. Curtin, Inventor:

By Emile Gembart
Attorney.

UNITED STATES PATENT OFFICE

PETER A. CURTIN, OF BUFFALO, NEW YORK

CUFF BUTTON

Application filed July 25, 1928. Serial No. 295,154.

My invention relates to improvements in cuff buttons; one of its objects being to provide a simple device of this character, easily securable to and readily removable from the cuffs of shirt sleeves, and wherein provision is made to permit the extension of the cuff button so that the sleeve may be drawn upwardly on the arm and retained in such position, which it is oftentimes found of advantage to do to prevent the soiling of the cuffs.

It also has for its object the production of a simple and inexpensive cuff button in which the link is made in the form of an extensible element readily replaceable from the heads of the button.

A still further object of my invention is the provision of a link cuff button in which an ordinary rubber band may be utilized as a shank or link connecting the two heads of the button, and in which novel means are provided for connecting the rubber band to the heads of the button.

With the above and other objects in view to appear hereinafter, the invention consists in the novel features of construction and in the arrangement and combination of parts to be hereinafter described, and more particularly pointed out in the subjoined 30 claims.

In the drawings:—

Fig. 1 is a perspective view of a link cuff button constructed in accordance with my invention, in a form which I now consider preferred.

Fig. 2 is a longitudinal section taken on line 2—2, Fig. 1.

Fig. 3 is a longitudinal section taken on line 3—3, Fig. 2.

Fig. 4 is an outer face view of one of the heads of the button.

Fig. 5 is an inner face view thereof.

Fig. 6 is a view of the button showing the shank thereof surrounded by a flexible 45 cover, which also serves as a spacing device for the heads.

Fig. 7 is a view of the rubber band forming the shank or link of the button and the retainer pins associated therewith.

Fig. 8 is a view of the cuff end of a shirt

sleeve, showing my improved button applied thereto.

Fig. 9 is a longitudinal section through one end of a button embodying my invention in modified form.

Figs. 10 and 11 are similar views of other modified forms of the invention.

The heads of the button may be constructed like ordinary garment buttons, with the exception that the heads would be provided with an oblong opening instead of two or more small openings for the passage therethrough of a fastening thread; but the invention may be used in conjunction with different types of heads, such as are illustrated, for example, in Figs. 9 to 11 of the drawings.

In Figs. 1 to 6 of the drawings, I have shown ordinary buttons formed of horn, bone, or other like material, and these I refer to as the heads of the cuff buttons and designate by the numeral 11. Each of these heads has centrally formed therein an oblong opening 12, and in the outer face of each head or button a concaved depression 13 is formed.

As the link or shank for connecting the two heads or buttons in desired spaced relation, I utilize a rubber band 14, the width of which is slightly less than the length of each of the openings 12 in the heads or buttons 11, so that the doubled-up ends of this band may be passed through the openings from the inner side of the heads or buttons, and as the combined thickness of the two stretches or sides of the rubber band is greater than the width of each of the slots, it is necessary to place in the folded portion of the rubber band, and more particularly against the bights of the band, a thin strip of metal or the like, over which the folded end of the band is stretched, so that the double thickness of the rubber and the thickness of the metallic strip will be less than the width of the openings 12 in the buttons. When the rubber is passed through these openings, while in a stretched condition, the folded ends inserted through the heads or buttons may be taken hold of and the metallic or other strip withdrawn from the

band. Retainer pins 15 are then slipped through the projecting ends of the band and positioned lengthwise over the oblong openings 12 in the direction of their length so that opposite ends of the pins extend beyond the opposite ends of said openings and bear against the heads or buttons 11 within the depressions 13. The rubber band is then pulled inwardly so that the bights 10 of the same will be brought firmly against the retainer pins in the manner best shown in Fig. 2, wherein the pins are shown spanning or bridging the openings 12 lengthwise. It is apparent that when stretching 15 a rubber band, it becomes narrower and thinner along the region stretched, and at such region possesses inherent expansive qualities which come into play immediately the stretching of such region ceases. Therefore, 20 the rubber band, at the regions confined in the openings 12 in the heads, is held against the walls of said openings by its inherent expansive qualities while stretched. This results in the formation of slight 25 shoulders on the bands where the stretched regions merge into the unstretched intermediate region of the band, and these shoulders bear against the inner sides of the button heads or impinge against the flared inner portions of the walls of the openings 30 in the heads when so arranged. In either case the normal thickness of the band at the ends of the unstretched intermediate portion prevent outward movement of the ends of 35 the band, or inward movement of the button heads on the band.

As clearly shown in Fig. 3, the rubber band will have its two sides or stretches lying in contact with each other and be slightly compressed within the openings 12 of the heads or buttons so that accidental removal of the pins from their seats within the depressions 13 will not readily occur. Retention of the pins against their seats is assured due to the bights or folded portions of the rubber band being prevented from moving outwardly away from the pins, owing to the stretches of the band between the two heads being unstretched and consequently thicker than the stretched portions within the openings 12, thus forming shoulders on the band which bear against the inner sides of the buttons at opposite sides of the openings therein and prevent outward movement of the band within said openings. This condition exists at all times, except when the cuff is moved upwardly on the arm to cause stretching of the band portions between the heads, at which time the strain on the rubber band will also positively hold the pins against their seats.

The rubber band is preferably of the length of the link or shank of a conventional link button, but is stretchable so that the sleeve can be drawn upwardly onto the arm

of a wearer and be so retained, or so that the shirt can be easily removed by the wearer without loosening the button from one end of the cuff, as is required when using the ordinary type of cuff button having a rigid link or shank connecting the heads thereof.

In Fig. 6 I have shown the link or shank of the button surrounded by an enclosure 16 in the form of a spiral spring, which is preferably cut to a length that it does not, when at full expansion, tend to stretch the rubber band or shank 14 proper. This spiral spring under full expansion simply bears against the inner sides of the heads or buttons and flexes with the stretchable link or shank. It is simply utilized to more or less conceal the rubber band, and if desired, the convolutions thereof may lie in contact one with another so as to fully conceal the band.

In the modifications shown in Figs. 9 and 11, the heads are formed of metal, and instead of the concaved depression shown in the preferred construction, each has a long and narrow depression 17 provided in the outer face of the head slightly larger than the retainer pin 15, and the end walls of this depression are made abrupt or formed at right angles to the bottom thereof, as at 18, so that the ends of the retainer pin have firm bearing against these end walls, which prevent the retainer pins from sliding lengthwise under any condition of use. The head shown in Fig. 9 is flat in cross section, while the head shown in Fig. 11, is concavo-convex; but in other respects they are alike.

In the modification shown in Fig. 10, a hollow head is provided, the head having a dished inner or rear member 19 through which the elongated opening 12 is formed, and by dishing this inner or rear member, a marginal wall 20 is provided, against which the ends of the retainer pin 15 bear. The front or open side of this dished portion may be covered with a front or facing member 21 having a flange 22 which encircles the inner or rear member and may be lapped over the rear thereof, as at 23. The face of this front or facing member may have any desired ornamentation, or lips 24 may be stamped therefrom for engaging any desired stone 25 placed against the front wall for ornamental or embellishing purposes.

Having thus described my invention, what I claim is:—

1. A cuff button, comprising two heads, each having a single slot therein and a stretchable link passed through said slots and detachably connected at opposite ends to the opposite heads, said link being compressed within the slots of said heads and having means at the outer side of each head to prevent its being removed from said slot under stretching of said link.

2. A cuff button, comprising two heads, each having a single oblong opening centrally therein, a stretchable link having opposite ends passed through said openings, and removable means on the exterior of said heads for detachably securing said link to said heads.
3. A cuff button, comprising two spaced heads, each having a single oblong opening centrally therethrough, a rubber band connected to said heads and having opposite folded ends inserted through said oblong openings from the inner sides of said heads, the bights of said rubber band extending outwardly beyond the outer faces of said heads, and a device at the outer sides of said heads bridging said oblong openings and having the bights of the rubber band drawn thereagainst in stretched condition.
4. A cuff button, comprising two spaced heads, an elastic band serving as a stretchable link connected at opposite ends to said heads, and a spiral spring surrounding said link and bearing at opposite ends against the inner sides of said heads, said stretchable link allowing movement of said heads away from the ends of said spring while maintaining said heads in restrained connected relation.
5. A cuff button, comprising two spaced heads, an elastic band serving as a stretchable link connected at opposite ends to said heads and normally holding said heads in spaced relation when unstretched, and a spiral spring surrounding said link and bearing at opposite ends against the inner sides of said heads without causing stretching of said link, said stretchable link allowing movement of said heads away from the ends of said spring while maintaining said heads in restrained connected relation.
6. A cuff button, comprising two spaced heads, each head having an oblong opening centrally therethrough and depressions in the outer faces of said heads adjacent said openings, a rubber band having its two stretches lying in contact one with the other and having the folded ends thereof passed through the openings in said heads, and retainer pins bridging the openings in said heads and having the ends thereof lying within said depressions and the bights of said rubber band drawn into contact with said pins.
7. A cuff button, comprising two heads spaced apart, each provided with an opening therein, a depression in the outer face of each head at opposite ends of said opening, a rubber band connecting said heads and having the folded ends thereof extended through said openings from the inner sides of said heads, and a retainer pin for each head of greater length than the width of said band spanning the opening in said head and projecting with opposite ends into said depressions, said pins being passed through said band at the folded ends thereof and having the bights of said band drawn firmly thereagainst.
8. A cuff button, comprising two heads spaced apart, each having an elongated opening centrally therein, a rubber band having its folded ends inserted through said openings in stretched condition, and detachable pins longer than said openings entered in the folded ends of said band and bearing against the outer sides of said heads at opposite ends of said openings.
9. A cuff button, comprising two heads, and a stretchable band detachably connected at its folded ends to opposite heads, said heads having slots through which said folded ends are passed while in stretched condition, the stretching of said ends forming shoulders at their points of connection with the intermediate unstretched portion of said band which bear against the inner sides of said heads, and means passing through said folded ends separate from said heads to prevent withdrawal of said stretchable band from said heads, the stretched folded ends of said bands preventing inward movement of said heads along said band.
- In testimony whereof, I affix my signature.
- PETER A. CURTIN.
